UNITED STATES PATENT OFFICE.

FRANK J. PETRUSHA, OF IRONWOOD, MICHIGAN.

DEVICE FOR HOLDING CARPETS.

1,216,602.

Specification of Letters Patent. Patented Feb. 20, 1917.

Application filed September 7, 1915. Serial No. 49,236.

To all whom it may concern:

Be it known that I, FRANK J. PETRUSHA, a citizen of the United States, residing at Ironwood, in the county of Gogebic and State of Michigan, have invented certain new and useful Improvements in Devices for Holding Carpets, of which the following is a specification.

My invention relates to improvements in devices for holding carpets or other floor covering upon stairways.

An important object of the invention is to provide a device of the above mentioned character, which is extremely simple in construction, inexpensive to manufacture, and attractive in appearance.

A further object of the invention is to provide a device of the above mentioned character so constructed that the attaching brackets are arranged beneath the carpet or floor covering and a portion of the device which is visible closely resembles a single continuous rod.

Other objects and advantages of the invention will be apparent during the course of the following description.

In the accompanying drawings forming a part of this specification and in which like numerals are employed to designate like parts throughout the same,

Figure 1 is a side elevation of a plurality of devices embodying my invention, showing them in use,

Fig. 2 is an enlarged side elevation of the device removed, a portion being shown in section,

Fig. 3 is a perspective view of one end of the device, the elements being separated,

Fig. 4 is a similar view of a key and holding socket, and,

Fig. 5 is a side elevation of a tube included in the invention.

In the drawings, wherein for the purpose of illustration is shown a preferred embodiment of my invention, the numeral 10 designates a plurality of steps, embodying horizontal and vertical portions 11 and 12. The steps are covered by a strip of carpet 13 or other floor covering.

The numeral 14 designates one of my improved attaching devices as a whole, which is arranged above a horizontal portion of the strip adjacent the vertical portion of the next step.

Each attaching device 14 embodies tubular holding sockets or sleeves 15 and 16,

each of which is provided at its inner end with a bracket 17, preferably formed integral therewith. This bracket embodies vertical and horizontal portions 18 and 19, 60 adapted to be attached by means of screws or the like to the vertical and horizontal portions 12 and 11 of the steps, as is obvious. The sleeve 15 has its outer end closed by a cap 15', as shown. As more clearly shown 65 in Fig. 1, the brackets 17 being disposed upon the inner ends of the tubular sockets or sleeves 15 and 16, are arranged beneath or behind the carpet 13, and are entirely covered thereby.

The numeral 20 designates a rod, preferably in the form of a tube, which is adapted to be arranged between the pair of holding sockets or sleeves 15 and 16, in end to end relation. This rod is preferably longitudinally extensible, and for this purpose is formed in sections 20' and 21', telescoping, as shown. By being adjustable, the tube 20 may be used in connection with carpets of different widths.

In Fig. 5, I have shown a single non-extensible tube 20^a, adapted to be substituted for the adjustable tube 20, if desired.

One end of the tubular rod section 21' is provided with a reduced extension 21, preferably a plug inserted therein, while the invention is in no sense restricted to this precise construction. The reduced extension 21 is adapted to be inserted within the inner end of the tubular pocket or sleeve 15, as 90 shown.

The numeral 22 designates a key, having a head 23 similar in shape and appearance to the head 15'. This key is adapted to be inserted within the socket or sleeve 16 and 95 is longer than the sleeve, to project inwardly beyond it, and enter the adjacent end of the tube portion 20', thus holding the tube 20 in place.

In the use of the device, the bracket 17 is 100 first attached to the steps 10 at the desired points and the carpet 13 placed upon the steps forwardly of or above these brackets to cover them. The reduced end 21 of the tube 20 is then inserted in the socket or 105 sleeve 15 and the key 22 moved into the socket or sleeve 16 and its inner end inserted in the adjacent end of the tube 20, thus holding it in place.

It is to be understood that the form of 110 my invention herewith shown and described is to be taken as a preferred example of the

same, and that various changes in the shape, size, and arrangement of parts may be resorted to without departing from the spirit of the invention or the scope of the subjoined claim.

Having thus described the invention, I claim:

A stair-way carpet holding device, comprising a pair of L-shaped brackets adapted to fit in the corner between the horizontal and vertical portions of the step and carrying outwardly projecting sleeves rigidly secured thereto, the sleeves being arranged wholly at one end of the brackets whereby the sleeves will be positioned adjacent the edges of the carpet when the brackets are arranged therebeneath; a cap closing the outer end of one sleeve; a rod to be ar-

ranged upon the carpet between the sleeves and provided at one end with a reduced projection to enter the corresponding sleeve, and having a recess formed in its opposite end; and a pin adapted for insertion through the other sleeve and being longer than the sleeve so that its inner end extends into the recess of the rod to lock the rod in place, said pin having a cap at its outer end which is identical with the first named cap; substantially as described.

In testimony whereof I affix my signature in presence of two witnesses.

FRANK J. PETRUSHA.
